UNITED STATES PATENT OFFICE.

JOHN H. NICHOLS, OF OILFIELDS, CALIFORNIA.

OIL-WELL PUMP.

1,417,764.

Specification of Letters Patent. Patented May 30, 1922.

Application filed April 7, 1921, Serial No. 459,401. Renewed February 27, 1922. Serial No. 539,752.

To all whom it may concern:

Be it known that I, JOHN H. NICHOLS, a citizen of the United States, residing at Oilfields, in the county of Fresno and State of California, have invented certain new and useful Improvements in Oil-Well Pumps; and I do declare the following to be a full, clear, and exact description of the invention, such as will enable others skilled in the art 10 to which it appertains to make and use the same.

This invention relates to an improved oil well pump and one object of the invention is to provide a pump in which the standing 15 valve and cylinder can be withdrawn from the well tubing by means of the sucker rod and plunger thus making it unnecessary to pull the tubing when it is desired to remove the standing valve and cylinder.

Another object of the invention is to provide improved means for engaging an extension of the standing valve so that ordinarily the movement of the sucker rod and plunger will not cause the standing valve and cylinder 25 to work loose.

Another object of the invention is to so construct the device that an enlargement formed upon the extension of the standing valve may pass easily between spring clutch 30 strips carried by the lower portion of the tubing, the spring clutch strips then engaging the upper end portion of the enlargement to hold the standing valve and cylinder against accidental displacement but permits 35 of their removal through the medium of the sucker rod and plunger when desired.

Another object of the invention is to so construct this pump that the standing valve may have working engagement with a valve 40 seat serving to support the standing valve and cylinder and further serving as means to fill the space between the lower portion of the standing valve and the walls of the tubing.

Another object of the invention is to provide an improved type of adjustable collar positioned in the tubing about the upper portion of the cylinder, the adjustable collar being provided with passages through which 50 oil may pass into the space between the cylinder and the well tubing.

This invention is illustrated in the accompanying drawings, wherein:

Figure 1 is a vertical sectional view 55 through the improved pump.

Figure 2 is a view showing the well tub-

ing and cylinder in vertical section, the standing valve, sucker rod, and plunger being shown in elevation.

Figure 3 is a transverse sectional view 60 taken along the line 3—3 of Fig. 1.

The well tubing or casing is formed in sections and will include a section 1 connected with an upper section 2 by means of a coupling 3 and connected with a lower 65 section 4 by means of a coupling 5. The coupling 3 is provided with an internal thickened portion forming an adjusting collar 6 provided with grooves 7 so that oil in the section 2 of the tubing may pass through 70 these grooves into the space between the section 1 and cylinder 8. The coupling 5 is also internally thickened to provide a downwardly tapering valve seat 9 for receiving the tapered lower portion 10 of the standing 75 valve 11. This standing valve has the cylinder 8 in threaded engagement therewith so that the standing valve is partly positioned within the cylinder. The tapered lower portion of the standing valve extends through 80 the valve seat 9 and carries a depending tubular extension 12 provided intermediate its length with an outstanding shoulder 13. This shoulder 13 tapers downwardly so that it may pass easily between the resilient an- 85 choring strips or dogs 14 secured to the lower tube section 4 and has its upper end extending abruptly toward the tube 12. It will thus be seen that when the standing valve and cylinder are lowered into the well 90 casing or tube, the downwardly tapered shoulder 13 may readily force its way between the resilient strips 14. The hook-shaped upper end portions of the strips 14 will grip the upper portion of this shoulder 95 and will thus serve to securely but releasably hold the standing valve and cylinder in place with the tapered lower portion of the valve seated in the tapered valve seat 9. A lift nut 15 is carried by the upper end of the 100 cylinder 8 and will be of such internal diameter that while it may fit loosely about the sucker rod 16, it will prevent the plunger 17 from moving out of the cylinder. Therefore, when the sucker rod and plunger are 105 drawn upwardly for removal from the well, the plunger will strike the inner end of the lift nut 15 and continued upward movement of the sucker rod will cause the cylinder and standing valve to be drawn upwardly out 110 of the well.

When this pump is in use, the lift nut will

first be placed upon the sucker rod and after the plunger 17 has been connected with the sucker rod, the plunger will be inserted into the cylinder 8 and the lift nut screwed tightly into engagement with the upper end portion of the cylinder. The sucker rod is lowered into the well casing or tubing and as the tapered portion 10 of the standing valve moves into engagement with the valve seat 9, the shoulder 13 will be gripped by the resilient strips or dogs 14. The pump can then be operated in the usual manner with the plunger reciprocating in the cylinder without striking the standing valve or lift nut. When it is desired to remove the cylinder and standing valve from the well for cleaning or repair purposes, it is simply necessary to draw the sucker rod upwardly and out of the well. As the sucker rod moves upwardly, the upper end of the plunger will engage the lift nut and the cylinder and standing valve will be carried upwardly and out of the well. When the standing valve moves upwardly off the valve seat, oil in the well tube or casing can pass down out of the casing or tubing into the lower portion of the well. This will permit of the sucker rod, plunger, cylinder, and standing valve being withdrawn without excessive effort. It will thus be seen that there has been provided a pump in which the cylinder and standing valve will be normally held in the proper position for pumping, but in which the pump is so constructed that the cylinder and standing valve may be easily and quickly removed for cleaning and repair without it being necessary to pull the tubing.

I claim:

1. In an oil well, a tubing, a sucker rod in the tubing, a plunger carried by the sucker rod, a cylinder and standing valve removably seated in the tubing, an anchoring element carried by and extending beneath the standing valve, resilient means carried by said tubing for engaging said anchoring element to releasably hold the cylinder and standing valve in place, and means carried by the cylinder engageable by the plunger whereby the cylinder and standing valve may be released from the gripping means and drawn out of a well with the sucker rod and valve.

2. In an oil well, a tubing, a standing valve, a cylinder carried by the valve, a seat

supporting the valve in the tubing and forming a filler for space between the valve and tubing, the standing valve being provided with a tubular lower extension extending beneath the seat and having an annular shoulder intermediate its length tapering downwardly from its upper end, spring strips carried by the tubing and having their free end portions extending for engaging the upper end of the shoulder, a sucker rod, a plunger carried by the sucker rod within the cylinder, and means carried by the cylinder engageable by the plunger for drawing the cylinder and standing valve out of the tubing with the sucker rod and plunger.

3. In an oil well, a tubing having an internal valve seat, a standing valve supported for removal in the tubing upon said valve seat and having a tubular lower extension extending beneath the valve seat, gripping means carried by the tubing beneath the valve seat for engaging the tubular extension to releasably hold the standing valve in place, a cylinder carried by the valve extending upwardly in the tubing, a sucker rod extending through the tubing into the cylinder, a plunger carried by the sucker rod within the cylinder, and a lifting nut carried by the cylinder for engagement by the plunger to lift the cylinder and standing valve out of the well with the sucker rod and plunger.

4. In an oil well, a tubing having an annular internal seat adjacent its lower end, resilient gripping means in the tubing below the seat, a sucker rod extending down into the tubing, a plunger carried by the sucker rod, a cylinder fitting in the tubing with the plunger positioned in the cylinder, a lift nut carried by the cylinder for engaging the plunger and suspending the cylinder upon the plunger, a standing valve carried by the cylinder for resting upon the internal seat of the tubing, and a tubular extension for the standing valve provided with an outstanding shoulder for engagement by the resilient gripping means to releasably hold the cylinder in a set position with the plunger movable longitudinally in the cylinder.

In testimony whereof I have hereunto set my hand.

JOHN H. NICHOLS.
